UNITED STATES PATENT OFFICE.

CHARLES W. PACKER, OF PHILADELPHIA, PENNSYLVANIA.

DESIGN FOR A CROSS-BAR FOR ICE-CREAM FREEZERS.

SPECIFICATION forming part of Design No. 22,276, dated March 7, 1893.

Application filed February 8, 1893. Serial No. 461,270. Term of patent 14 years.

To all whom it may concern:

Be it known that I, CHARLES W. PACKER, a citizen of the United States, and a resident of Philadelphia, Pennsylvania, have invented 5 a certain Improved Design for a Cross-Bar for Ice-Cream Freezers, of which the following is a specification.

My design is fully shown in the accompanying drawing, which represents a perspective view of the cross bar.

The distinctive feature of the design is the central box or casing A which is in the shape of a horse shoe, and has upon its upper surface the representation of a horse shoe as shown at B. From the central box A project 15 two arms D and F, the latter arm being open, that is to say, consisting of opposite sides con-

nected by an end plate. The arm D has upon the top a boss a, and the arm F has at one end a projecting lug b, but these are unimportant features, the essential feature of the design being the central horse-shoe-shaped box or casing with oppositely projecting arms.

I claim—

The design for a crossbar for ice cream 25 freezers, substantially as described and as shown in the accompanying drawing.

In testimony whereof I have signed my name to this specification in the presence of two subscribing witnesses.

CHARLES W. PACKER.

Witnesses:

FRANK E. BECHTOLD,
JOSEPH H. KLEIN.
